UNITED STATES PATENT OFFICE

2,618,086

BADGE CLIP

Louis J. Komoreus, Chicago, Ill., assignor to
Parisian Novelty Company

Application February 25, 1950, Serial No. 146,174

5 Claims. (Cl. 40—1.5)

1

This invention relates to a badge assembly, and more particularly to a device for carrying a name plate on a particular part of one's clothing, such as a lapel, an open pocket or the like.

Devices of the type described have usually been formed of an envelope of transparent material in which a name plate can be inserted. The rear wall of such device has usually been provided with a pin affixed thereto for attachment to a proper part of the wearer's clothing. The use of pins constitutes an objectionable feature and the means for affixing the pins to the rear wall of the envelope is often difficult and expensive in a disposable item of this type.

It is an object of this invention to provide a badge assembly in which a new and novel fastening arrangement is employed.

Another object is to produce a new and novel clip member which may be used in combination with a name plate receiving envelope to provide a simple and low cost assembly in which attachment of the clipping member with the envelope is expeditiously and economically achieved without the use of expensive parts or experienced labor. The assembly is characterized by means for permitting mounting in the proper part of one's clothing without being subject to the objectionable feature of pins and without fear of inadvertent disengagement.

These and other objects and advantages will hereinafter appear, and for purposes of illustration but not of limitation an embodiment is shown in the accompanying drawing in which,

Figure 1 is a fragmentary view showing a device embodying features of this invention in position of use on the lapel of a man's suit coat.

Figure 2 is a perspective view of the name plate assembly.

Figure 3 is a perspective view of the assembly shown in Figure 2 with the parts separated.

Figure 4 is a sectional elevational view of the assembly shown in Figure 2, and

Figure 5 is a sectional elevational view of the assembly in its position of use on the lapel of the wearer.

As shown in the drawing, the name plate assembly 10 embodying features of this invention is adapted to be positioned on a part of one's clothing having a free upper edge, such as the lapel 11 of a coat 12, or the upper edge of an outer pocket wall or the like.

The device is formed essentially of two parts, the name plate receiving member 13 and the clipping member 14. These two parts need no other elements to effect their assembly, and may be

securely fixed to an appropriate part of one's clothing in an expeditious manner.

The envelope part 13, in which the name plate 15 may be removably positioned, comprises an envelope formed of a transparent front wall 16 and a spaced back wall 17 which may be connected together at their upper and lower edges to provide an assembly having at least one open end 18 through which the name plate 15 may be inserted. As shown in the drawing, it is convenient to form the name plate receiving member 13 out of a single sheet of transparent plastic material which is folded crosswise intermediate its ends to provide the desired front wall 16, spaced from the back wall 17. The lower edge portion of the front wall may be folded up rearwardly to provide a receiving groove or flap 19 in which the lower edge of the back wall 17 may be received to provide an envelope having open ends through which the name plate 15 may be inserted. The flap portion 19 may extend in an upwardly and forwardly direction to provide a restricted spaced relation for gripping the rear wall portion 17, inserted therein.

In the upper region of the rear wall 17 intermediate its edges, there is provided a pair of vertically spaced, horizontally disposed, narrow slots 20 and 21 respectively which are adapted to receive a part of the clip member in securing relation.

The clip member 14 comprises a pair of spaced walls 22 and 23 formed of relatively rigid material connected together at one end. One wall is formed with stops 24 intermediate its ends to provide a sharp setoff 25 facing towards the connected portion and the free end portion of the other wall may be flared outwardly to facilitate the clip member's positioning on the appropriate part of one's clothing. More specifically, the clip member is formed of a strip of spring metal having a thickness corresponding to the width of the slots 20 and 21. The metal is bent to U shape to provide a pair of spaced walls 22 and 23 which may approach each other in the region of their free ends to provide a restricted opening 26, while the end portions 27, flared outwardly, facilitate positioning on the clothing, as previously pointed out. A portion of the outer wall 22, intermediate its ends, is struck inwardly to provide sharp offsets 25 or abutments facing in the direction of the connected end. The inwardly struck portions are spaced from the connected end by a distance corresponding to that which will enable the offset to be positioned just below the lowermost slot 21 when the wall 22 is passed downwardly

through the upper slot 20 into the region between the walls 16 and 17 of the envelope and then outwardly through the bottom slot 21, as shown in Figures 4 and 5.

In effecting the assembly, it is only necessary to insert the edge portion of the wall 22 through the upper slot 20 from the outside and then to return the lower edge of the wall 22 to the outside through slot 21. The clip is then forced downwardly relative to the envelope portion until the upper shoulder or stops 25 of the inwardly struck portions 24 pass through the lower slot 21. In this assembled relation, relative movement between the parts is limited by the fact that the upper connected end of the clip member 14 cannot pass through the upper slot 20 while the offset portions or stops 24 prevent return or upward movement of the clip member 14 relative to the name plate member 13.

When it is desired to mount the device as a badge, the name plate 15 is slipped between the walls 16 and 17 from one side and then the free edge of the clothing on which the badge is to be positioned is merely inserted between the walls 22 and 23 of the clip member. Frictional engagement is established between the clip member and the part of the clothing disposed therein and the inwardly extending stops or offset portions 25 function further to engage the clothing in a manner which prevents inadvertent upward movement of the clip relative to the clothing on which it is mounted. For disengagement, the envelope portion may be pulled upwardly to disengage the offset portion from the clothing and permit easy removal.

It will be understood that numerous changes may be made in the details of construction, operation and arrangement without departing from the spirit of the invention especially as defined in the following claims.

What is claimed is:

1. A name plate receiving device comprising in combination a name plate receiving member having a transparent outer wall and an inner wall formed with a pair of vertically spaced horizontally disposed slots, and a clip member in the form of a pair of spaced walls connected together at their upper ends with one wall passing forwardly through the upper slot and rearwardly through the bottom slot to provide an intermediate portion disposed between the walls of the name plate receiving member, and a stop extending inwardly from the latter wall at a point just below that portion extending through the lower slot.

2. A name plate receiving device comprising a name plate receiving member having a transparent outer wall and an inner wall formed with a pair of vertically spaced horizontally disposed slots, and a clip member in the form of a pair of spaced walls of spring metal connected together at their upper ends with one wall passing forwardly through the upper slot and rearwardly through the bottom slot, said wall having inwardly struck portions just below that portion extending through the bottom slot to provide an offset which engages the upper wall of the bottom slot and prevents disengagement.

3. A name plate receiving device comprising a name plate receiving member having a transparent outer wall and an inner wall formed with a pair of vertically spaced horizontally disposed slots, and a clip member comprising a pair of spaced walls having a width corresponding to the width of the slots and formed of a single strip of spring metal bent to U shape, the outer wall of the U-shaped member passing through the upper slot into the region between the walls of the name plate receiving member and returning through the lower slot into the region outside said member, said wall having inwardly struck portions intermediate its ends to provide sharp offsets in that portion of the wall extending beyond the lower slot.

4. The name plate receiving device as claimed in claim 3 in which the other wall of the U-shaped member has an outwardly flared end portion.

5. The name plate receiving device as claimed in claim 3 in which the name plate receiving element has open ends for permitting the name plate to be inserted endwise therein.
